FARM IMPLEMENT DISK SHARPENER

John H. Harth, Mendota, Ill.

Application May 5, 1936, Serial No. 78,026

1 Claim. (Cl. 51—209)

This invention relates to sharpeners which are especially adapted for sharpening disks of farm implements and has for the primary object the provision of a portable device of this character which may be easily brought into engagement with the rotating implement disk with desired force and at a selected angle thereto whereby the disk will be sharpened with any desired bevel to the cutting edge thereof.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a perspective view showing a sharpener constructed in accordance with my invention and associated with disks of a farm implement.

Figure 2 is a fragmentary sectional view showing the mounting of the sharpening element on its support.

Figure 3 is a perspective view illustrating a modified form of my invention.

Referring in detail to the drawing, the numeral 1 indicates a post, one end of which has secured thereto a pointed rest 2 to engage with a support of any desired kind. A handle 3 is secured to the post adjacent to the end thereof and extends at right angles to said post. An axle 4 is removably secured to the post 1 and rotatably

supports a sharpening wheel or disk 5 constructed of any suitable material.

In operation, disks 7 of a farm implement are suitably supported and rotated and the post is positioned on a support adjacent thereto so that the sharpening element 5 may be brought into contact with the disk adjacent to its periphery with desired force to bring about efficient sharpening of the disk. The post 1 is manipulated on the support manually by employing the lever 3.

Referring to the modified form of my invention shown in Figure 3, a metallic post 8 of angle iron construction is employed and has one end reduced to form a pointed rest 9 and said post adjacent its other end has the handle 3 secured thereto. The axle of the sharpening element is removably secured to the post 8 in the same manner as when secured to the post 1.

Having described the invention, I claim:

A sharpener comprising a post of angle iron construction having one flange extending beyond the other flange at each end thereof, one extended end portion of the longer flange being reduced to provide a rest upon which the post is adapted to be rocked, the other extended end portion of the longer flange being reduced to provide a handle, said longer flange, rest and handle being in the same vertical plane, a second handle secured to said longer flange adjacent said first handle and extending at right angles to said longer flange, and a sharpening element journaled to said longer flange intermediate said first handle and said rest.
